UNITED STATES PATENT OFFICE.

LLOYD G. COPEMAN, OF FLINT, MICHIGAN, ASSIGNOR TO COPEMAN LABORATORIES COMPANY, OF FLINT, MICHIGAN, A CORPORATION OF MICHIGAN.

REFRIGERATOR.

Application filed June 14, 1924. Serial No. 720,035.

This invention relates to a refrigerator, and is particularly directed to a cast-stone refrigerator that may be entirely formed by one casting operation, and has for its object 5 means whereby the inner shell and outer shell may be cast-united together.

In such a construction it is essential that the conductivity of the heat from the outside to the interior of the refrigerator be 10 broken and means are provided for casting a heat insulating frame in the refrigerator, the inner and outer shells being both cast-united to said heat insulating frame.

In the drawings: 15 Fig. 1 is a sectional view through the moulds showing how the fibrous strip may be floated therein in preparation for the pouring operation.

Fig. 2 is a similar sectional view after the 20 cementitious material is poured in the mould.

Fig. 3 is a section taken on the line 3—3 of Fig. 2.

Fig. 4 is a vertical section through the 25 completed refrigerator taken on the line 4—4 of Fig. 3, the mould frames being removed.

Fig. 5 is a detailed plan view showing how the inner mould member which separates the 30 inner shell from the outer shell may be held in place.

Fig. 6 is a detailed perspective view of the fibrous frame to which the inner and outer shells are cast-united.

35 *a* designates the outer shell which comprises side walls *b*, a top wall *c*, a bottom wall *d* and a front wall *e*.

The front wall is provided with a plurality of door openings *f*. The inner shell *g* 40 is provided with a plurality of food chambers *h*, which are adapted to register with the door openings *f* in the front wall of the outer shell when the inner and outer shells are assembled together. A fibrous frame 45 structure *i* is provided with a plurality of door openings *j* which are identical in shape as the door openings *f* in the front wall of the outer shell.

I desire to pour the inner and outer shells 50 with one pouring so that the entire refrigerator shell may be made by one operation. As shown in Figs. 1, 2 and 3, this would comprise a bottom base structure *k* and the side walls *m* which may be bolted to the 55 base structure and to each other. This base

structure is provided with the inwardly extending bosses or cores *n* which are adapted to form the inside of the inner shell so as to form a plurality of food chambers within the inner shell. Corner plates *o* are bolted 60 or otherwise secured to the side walls *m* of the mould, and bolted to these corner plates as at *p* is the intermediate mould members *q*.

The fibrous frame *i* is floated within the 65 mould by means of the screws or other suitable devices *r* which are accessible from the inside of the core *n*, and this securely positions the fibrous frame so that the plastic cementitious material may flow around the 70 fibrous frame during the pouring operation. I provide a plurality of fastening devices, which are here shown as large-headed nails, which are driven part way into the fibrous frame. The mould part *q* is adapted to rest 75 on this fibrous frame and, as shown in Fig. 1, the mould is assembled together in readiness for the pouring operation.

Fig. 2 shows how the cementitious material is poured in the mould and how the 80 moulding material flows all around the fibrous frame member, the fastening devices being embedded in the stone work, thus securing the inner and the outer shells to said fibrous frame, thereby forming a refrigerator structure in which the outer and inner shells are cast-united together to form 85 a rigid and strong unit.

The fibrous strips *t* are cast-united to the 90 back wall of the inner shell by the fastening devices *u*. I secure a back plate *v* to these fibrous strips carried by the inner shell by means of the fastening devices *w*. The fibrous strips *x* are floated in the mould, so that when the outer shell of the refrigerator is poured these strips are located in the outer shell and the fastening devices *z*, here shown as nails, are driven through the back plate into this fibrous strip cast-united 95 with the outer shell. In this manner the rear end of the inner shell is supported in spaced relation with respect to the outer shell, the inner shell being additionally supported at the front by means of the fastening devices *s* which tie the inner shell to the fibrous frame *i*, which is in turn keyed to the outer shell.

Any insulating material 1 may be packed 105 into the space between the inner and the outer shells for providing an insulating me- 110

dium therebetween to positively break the conductivity of heat from the exterior to the interior.

What I claim is:

5. 1. In a refrigerator, the combination of an inner shell, and an outer shell including side walls and cast-united together in telescoped but spaced relation.
10. 2. In a refrigerator, the combination of a moulded inner shell, an outer moulded shell and cast united thereto, and means for breaking the heat conductivity between the shells.
15. 3. In a refrigerator, the combination of moulded stone inner and outer shells cast united together, the outer shell having side walls formed integrally therewith.
20. 4. In a refrigerator, the combination of an outer moulded shell provided at the front with door openings, and an inner moulded shell provided with food chambers in registration with said door openings, the said inner and outer shells being cast-united together.
25. 5. In a refrigerator, the combination of a moulded inner shell, an outer shell, and a fibrous frame to which said shells are cast-united for insulating the shells from each other.
30. 6. In a refrigerator, the combination of a moulded outer shell provided with door openings at the front and having side walls cast therewith, a fibrous frame provided with door openings of like size and cast-

united to said outer shell, and a moulded inner shell provided with food chambers which registers with the door openings, said inner shell cast-united to said fibrous frame.

7. In a refrigerator, the combination of a moulded outer shell provided with door openings at the front, and integrally formed side walls, a fibrous frame having door openings of like size, the outer shell cast-united to one side of said frame, and a moulded inner shell cast-united to the other side of said frame.

8. In a refrigerator, the combination of a moulded outer shell including side walls, a fibrous frame cast-united to the front of the outer shell and to a part of the side walls, an inner shell cast-united to said fibrous frame and spaced from the side walls of the outer shell, and means for supporting the inner shell at the rear thereof in such spaced relation with respect to said side walls.

9. In a refrigerator, the combination of a moulded outer shell including side walls, a fibrous frame cast-united to the outer shell at the front, a moulded inner shell cast-united to said fibrous frame and spaced from the side walls of the outer shell, and a back plate secured to the rear of the inner shell and to the side walls of the outer shell for supporting the rear of said inner shell in such spaced relation.

In testimony whereof I have affixed my signature.

LLOYD G. COPEMAN.
